UNITED STATES PATENT OFFICE.

ERNST G. K. ANDERSON, OF CHICAGO, ILLINOIS, ASSIGNOR, BY MESNE ASSIGNMENTS,
TO APPLETON ELECTRIC CO., OF CHICAGO, ILLINOIS, A CORPORATION OF ILLINOIS.

FOCUSING DEVICE FOR ELECTRIC LAMPS.

Application filed May 31, 1921. Serial No. 473,647.

To all whom it may concern:

Be it known that I, ERNEST G. K. ANDERSON, a citizen of the United States, and a resident of Chicago, in the county of Cook 5 and State of Illinois, have invented certain new and useful Improvements in Focusing Devices for Electric Lamps; and I do hereby declare that the following is a full, clear, and exact description thereof, reference being had to the accompanying drawings, and 10 to the characters of reference marked thereon, which form a part of this specification.

This invention relates to improvements in focusing devices for lamps designed to give 15 axial movement to an electric lamp for the purpose of accurately focusing it with respect to the focal axis of the reflector of a lamp casing and for locking the lamp in adjusted focal positions. The invention is 20 herein shown as adapted to be a universally directable spot lamp but is capable of general use where like conditions prevail.

The object of the invention is to provide 25 an exceedingly simple and economical device for the purpose set forth which is made of few simple parts; which is constructed so as to permit focal adjustment of the lamp without interfering with the operation of the lamp structure or its mounting, and 30 to otherwise simplify and improve focal adjusting devices for the general purpose set forth.

In the drawings:

Figure 1 is a side elevation, with parts 35 broken away, of a spot lamp equipped with a focus adjusting device embodying my invention.

Figure 2 is a plan view of the parts shown 40 in Figure 1, with other parts broken away.

Figure 3 is a plan view of the rearwardly extending stem of the lamp casing, showing 45 parts of the focusing device in plan view.

Figure 4 is a transverse section on the 50 line 4-4 of Figure 1.

As shown in said drawings, 10 designates 55 a portion of the lamp casing and 11 the usual electric lamp bulb adapted to be arranged in the focal axis of a reflecting or mirrorized surface of the casing or a part carried thereby. 13 designates a stem which extends rearwardly from the lamp casing to constitute a handle by which the lamp can be directed. Said stem is enlarged and internally threaded at its forward end 14 to

engage an externally threaded stud 15 of a plate 16, that conforms to and is fixed to the rear side of the casing. The stem is internally recessed to receive said stud 15, so that the bore of the stem is flush with the bore of the stud to slidably receive a socket 17 for the usual base 18 of the lamp, the base being held in the socket by the usual bayonet joint structure shown in Figure 2.

19 designates a hollow branch or lug 65 which is made integral with the stem 13 to constitute, in connection with the tube 20, part of the universal mounting of the lamp, the parts being made hollow to receive the lamp cord 21. In practice, the 70 controller switch for the lamp circuit can be located in said stem, comprising, in part, the conductors 22, 23, that are connected to the socket terminals. Such a switch is shown in my companion application for 75 United States Letters Patent filed on the 25th day of June, 1921, Serial Number 480,347, and is a switch mechanism adapted to be exteriorly operated by an actuator member 24.

The said stem 13 is provided on its upper side near the lamp casing with a thickened portion or boss 25 which is cut away to provide a narrow slot 26, said slot being located over the rear end of the socket 17 and elongated in the direction of the axis of the socket. 80 27 designates a plate which is supported on the pad 25 and is slidable towards and from the lamp casing. The said plate is shown as held laterally in place on the pad by means of downwardly extending flanges 28 that embrace the sides of the boss. The plate is provided in line with said slot 26 with an opening to receive a 85 screw 29. Said screw is formed at its top with a slotted head 30 and the threaded shank of the screw extends with a close fit through the opening in the cover plate 27 and through the slot 26 of the boss and has 90 screw threaded engagement with the lamp socket 17. As herein shown, the threaded connection of said screw with the socket embraces threads formed partly in the cylindric wall of the socket and partly in a recess 95 31 in the rear end wall of the socket.

With the parts shown as assembled in Figures 1 and 4, the clamping pressure of the screw 29 coacts between said plate 27 and the socket to frictionally hold the plate 100 tight on the pad and thereby hold the 110

socket and the lamp from axial movement. When the screw 29 is released or loosened the lamp socket and the base and lamp carried thereby can be adjusted lengthwise of the stem 13 so as to move said lamp into proper focal relation to the axis of the reflector, the slot 26 being made of sufficient length to permit ample movement of the socket for this purpose. When the parts 10 are thus shifted, after loosening the screw, the cover plate 27 also moves with the screw, which it can now easily do by reason of the release of friction between the plate and boss, and the overlap of the cover plate 15 beyond the ends of the slot is sufficiently great to maintain the said slot always covered throughout any required movement of the parts associated with said screw to bring the lamp in proper focal relation to the reflector.

When the focal adjustment has been fixed and the screw 29 is turned tightly down on the cover plate 27, the effect of the tightening of the screw has three important functions; first, it locks the socket and the lamp base carried thereby fixedly in position or free from longitudinal movement in the stem 13; second, the drawing of the socket and the cover plate, which latter possesses 30 some springiness or deformability, toward each other through the action of the screw 29 serves, in the manner of a lock, to hold the screw from turning backwardly, and, third, the said screw serves as a means to 35 fixedly hold the cover plate 27 down over the slotted portion of the boss and to thereby provide a water proof joint which will prevent the entrance of dust or the elements into the interior of the shank or stem 13.

40 Thus it will be seen that when the focal adjustment is made it will be reliably maintained through the action of the screw that is threaded into the socket and bridged across the slot 26 between the socket and cover plate. It is also to be observed that the focal adjustment may be quickly and 45 readily made with the use of a simple tool, as a screw driver, by merely slackening the screw 30, moving the cover plate and screw 50 in the direction desired, which carries with it the socket and the lamp, and afterwards tightening the screw to lock the parts in place. This adjustment can be made without in any manner deranging the other parts

of the lamp or modifying the function of 55 the lamp.

The flanges 28 of the cover plate serve as means to prevent twisting movement of the cover plate on the pad 25 and aids in holding said cover plate in position, to at all 60 times, cover the slot 26 to prevent entrance of foreign matter therethrough into the hollow shank or stem and in contact with the terminals between the lamp case and the contacts of the socket through which current 65 is carried to the lamp filaments. Furthermore, the width of the slot 26 is such, with respect to the diameter of the screw 29, that said slot constitutes a guide for the screw and the depth of the guide slot is such as to provide 70 a wide bearing between the sides of the slot and said screw. The parts are thus held in fixed guiding relation, even when the screw is slackened to permit lamp focal 75 adjustment of the lamp bulb.

It will be understood that the structural details of the invention shown and described may be somewhat varied without departing from the spirit of the invention or sacrificing the advantages of the illustrated embodiment, and that the invention is not limited to said details shown, except as to parts which are herein made the subject of a specific claim, and as imposed by the prior art.

I claim as my invention:

A focusing device for electric lamps comprising, in combination with the reflector of a lamp, a tubular member coaxial with the focal axis of the reflector having an intermediate depending pivotal support dividing said member into a forward lamp supporting portion and a rearward handle portion, a focal adjustment member telescopically slidable in the end of said forward portion and provided at its inner end with means for the attachment to a lamp socket, said forward portion being provided with an elongated slotted boss, a laterally flanged plate forming a cover over said slotted boss; and an adjustable locking device passing through said cover plate and extending through said slot into said focal adjustment member.

In witness whereof I claim the foregoing 105 as my invention, I hereunto append my signature this 27 day of May, 1921.

ERNST G. K. ANDERSON.
